(57) **CLAIM**

The ornamental design for a precious stone jewelry setting, as shown and described.

DESCRIPTION

FIG. 1 is a perspective view of the precious stone jewelry setting showing my new design.

FIG. 2 is a front view of the precious stone jewelry setting of FIG. 1.

FIG. 3 is a rear perspective of the precious stone jewelry setting of FIG. 1.

FIG. 4 is a right side elevation view of FIG. 1, the left side elevation view being a mirror image thereof.

FIG. 5 is a cross-sectional view thereof, taken along lines 5-5 in FIG. 2; and,

FIG. 6 is a rear view of FIG. 1.

The broken lines in the drawings illustrate portions of the precious stone jewelry setting that form no part of the claimed design.
